UNITED STATES PATENT OFFICE.

OSIAS O. KRUH, OF SCHENECTADY, NEW YORK, ASSIGNOR TO GENERAL ELECTRIC COMPANY, A CORPORATION OF NEW YORK.

VAPOR ELECTRIC LAMP.

1,079,708.

Specification of Letters Patent. Patented Nov. 25, 1913.

Application filed June 22, 1903; Serial No. 162,499.

To all whom it may concern:

Be it known that I, OSIAS OTTO KRUH, a subject of the Emperor of Austria-Hungary, residing at Schenectady, in the county of 5 Schenectady and State of New York, have invented certain new and useful Improvements in Vapor Electric Lamps, of which the following is a specification.

My invention relates to improvements in: 10 the construction and operation of vapor electric lamps or rectifiers, and more especially to vapor electric lamps arranged for use with alternating-current circuits.

One of the principal objects of my invention is to render the starting of such a lamp 15 instantaneous.

Certain other objects of my invention of a minor nature, together with the details of construction and mode of operation of apparatus built in accordance with my invention, will be set forth more at length in the following description which is to be taken 20 in connection with the accompanying drawings.

25 The novel features of my invention are pointed out with particularity in the appended claims.

In the drawings Figure 1 represents one embodiment of my invention and Figs. 2, 30 3 and 4, modified forms.

In Fig. 1 the exhausted envelop of the lamp is of generally tubular form as indicated at 1. The lower portion of the tube is provided with a small tube 2 laterally offset from the main tube and communicating therewith as indicated. The lower ends of the tubes 1 and 2 form pockets which are filled with mercury sufficient in amount to bridge over the wall 3 which separates the 35 pockets of the depending portions of the tubes 1 and 2. The bodies of mercury 4 and 5 in these pockets constitute electrodes.

In the space between the tubes 1 and 2 is located a small auxiliary electrode 6 of 45 graphite or other suitable material connected to an external circuit by a suitable leading-in conductor.

In the upper portion of the tube 1 are located three electrodes 7, 8 and 9 of a suitable 50 composition such as graphite, which elec-

trodes are connected through leading-in wires with external circuits in a manner about to be described. The electrode 9 is provided with a filament 10 of carbon extending downwardly therefrom and, passing through a suitable anchoring device 11 or the like, into proximity to but not into contact with the body of mercury in the bottom of the tube. 55

A hermetically sealed glass tube 12, filled 60 with iron wires 13 to form an armature, floats in the body of mercury and is arranged so as to be under the influence of a solenoid 14. When this solenoid is energized the tube is withdrawn more or less 65 from the mercury thus laying bare the bridge 3. When this operation takes place the bodies of mercury in the two pockets 4 and 5 constitute separate electrodes. The electrode 4 serves as one of the main electrodes of the lamp, while the electrode 5 together with the electrode 6 constitute starting electrodes which operate in a manner 70 presently to be described.

Single-phase current is derived from any 75 suitable source and is conveyed to the lamp over mains 15 and 16. Before the lamp is started, these mains are connected, one through the solenoid 14 with the body of mercury 5 and the other to the electrode 6. 80 These mains are also connected, through the energizing coils 17 and 18 of a pair of cut-outs, to the main electrodes 7 and 8 in the top of the lamp.

The adjacent electrode 9 is provided with 85 means whereby a high voltage may be temporarily impressed thereon, and to this end it is connected to one terminal of the secondary 19 of a transformer, the other terminal of which is connected to the cooperating 90 main electrode 4 as indicated. The primary 20 of this transformer may be fed in a number of different ways, as indicated in the respective figures of the drawing, but in the particular embodiment shown in Fig. 1 it 95 is connected in multiple with one of the two inductance coils 21 and 22 which are joined in series across the mains 15 and 16. The purpose of these inductance coils is to store and restore energy so that when the lamp is 100

in operation, either at starting or under normal running conditions, there may be no instant when an arc is not flowing between some one pair of electrodes in the lamp. Unless 5 a continuous series of overlapping arcs in the tube were assured the lamp would not operate with alternating current. Inasmuch, however, as the application of the inductance coils 21 and 22 to an apparatus 10 of the type described is not of my invention, I do not consider it necessary in the following description to enter into any great detail as to the theory of operation of these inductances.

15 In the operation of starting the lamp, current flows from the main 16, through the inductance coil 22 to lead 23, and thence by way of the mercury bodies 4 and 5 through the solenoid 14 to the main 15. The solenoid 20 then operates to cause the withdrawal of the tube 12 so as to lower the level of the mercury below the wall 3. The current in this circuit is thus caused to jump across the open space between the bodies of mercury 4 25 and 5 thus separated and thereby produces an arc. This arc sets free ionized mercury vapor which has the effect of rendering the space between the electrode 6 and the mercury 4 electrically conducting. An arc then 30 springs between the two electrodes 4 and 6. In sustaining the two arcs thus formed, current of one polarity flows from the main 15 to the electrode 5, then through the arc over the bridge 3 to the main mercury electrode 4, 35 then back through the lead 23 to the junction point 24, and from thence through the inductance coil 22 to the other main 16. In a similar manner current of opposite polarity flows from the main 16 to the electrode 6, 40 thence through the arc to the main electrode or body of mercury 4, thence through the lead 23 to the junction 24, and so through the other inductance coil 21 to the main 15. It is to be understood that current flows alternately from these two mains 15 and 16. In 45 either case it passes through one or the other of the inductance coils 21 and 22. When therefore the current in either of these coils commences to fall from its maximum value 50 the coil discharges around the local circuit afforded by one or the other of the electrodes 5 and 6, as the case may be, and the lead 23 from the electrode 4 to the junction 24. Each discharge lasts longer than a half 55 period, so that there can therefore never exist a moment, no matter how short, when current is not flowing in the form of an arc between each of the electrodes 5, 6 and the main electrode 4. The production of ionized 60 vapor thus goes on continuously and no interruption in the flow of current from the alternating-current source takes place. The condition of operation, that one arc cannot

start unless there be a pre-existing arc, is therefore satisfied.

When the arcs thus described are started, the high voltage induced in the secondary 19 by the passage of current through its primary, though not sufficiently high, if acting alone, to produce an arc, cooperates with the 70 previously started arcs to cause an instantaneous starting up of an arc in the main tube between the electrode 9 and the electrode 4 to which the secondary is connected. This operation, due to the conductivity thus 75 imparted to the space in the main tube, causes the arcs previously existing between the electrode 4 and the electrodes 5 and 6, respectively, to be communicated instantaneously to the upper main electrodes 7 and 8. 80 The current which then flows in the leads extending to the electrodes 7 and 8 therefore energizes the solenoids 17 and 18 which thereupon operate upon the contact-making devices controlled by their respective armatures, and thus open the circuits of the two electrodes 5 and 6 and also the circuit of the primary 20 of the transformer by which a high voltage is impressed on the starting electrode 9. The transformer mentioned 90 might however be left in circuit though it is preferable that it be cut out of circuit since except at starting it performs no particularly useful service, while at the same time if the electrode 9 remain in circuit the filament 10 connected thereto is apt to disintegrate under the influence of alternating 95 current.

In the arrangement thus described in connection with Fig. 1 it will be noticed that 100 the primary 20 of the starting transformer is not traversed by the total current passing to the lamp but only by a fractional portion thereof. This construction is rendered necessary by the fact that if the primary were to 105 be so connected as to be traversed by the total current going to the lamp, then, upon interruption of the secondary, the reaction produced upon the primary would so interfere, even though momentarily with the flow 110 of current to the lamp that the latter would go out. The connection of the transformer is therefore made so that the secondary is not inductively related, so to speak, to the entire lamp current.

To secure the same result various other connections may be employed than that shown in Fig. 1, as for example that shown in Fig. 2. In this figure the construction of the lamp is represented as identical with 120 that shown in Fig. 1 and therefore requires no further explanation. The chief difference in the figures relates to the connection of the starting transformer. This transformer has its primary 25 connected in parallel with an 125 inductance 26 in series with one of the sup-

ply mains 27. The secondary 28 of this transformer is connected between the filament-carrying starting electrode 29 and the lower main mercury electrode 30. The circuit of this secondary is arranged so as to be interrupted by the operation of a cut-out magnet 31 which comes into action when the lamp starts as has been described in connection with Fig. 1.

10 In Fig. 2 the cut-out magnet 31, when it cuts the secondary 28 out of circuit, leaves the primary 25 and the inductance coil 26 still in circuit. If desired the cut-out magnet may be arranged, as indicated at 32 in Fig. 3, so as to short-circuit the windings 33 and 34 corresponding respectively to the windings 25 and 26 in Fig. 2. The secondary 35 is not disturbed as to its connections but becomes inert as soon as its primary is short-circuited. The cut-out 32, when it operates, opens a circuit between the contacts 36, thus cutting out the electrode 37 corresponding to the electrode 6 in Fig. 1, and at the same time, by bridging over the contacts 38, 25 short-circuits the coils 33 and 34 as before mentioned.

In the organization shown in the figures already described, the primary of the starting transformer is traversed by a greater 30 or less proportion of current flowing to the lamp. If desired, however, this starting transformer may be made entirely independent of the current in the lamp, in which case the connections may assume the form shown 35 in Fig. 4. In this figure the secondary of the starting transformer is indicated at 39 and is connected, in the same manner as shown in Fig. 3, to a pair of electrodes of the lamp. This lamp is the same as the 40 lamp shown in the preceding figures of the drawings and so requires no separate description. The primary of the transformer is indicated at 40 and is connected through a cut-out switch 41 directly across the supply mains 42 and 43. When the lamp starts up in the manner heretofore described, the cut-out operates to cut the primary 40 out of circuit and at the same time opens the 45 circuit of the starting electrode 44.

50 Although I have described my invention as applied to a vapor lamp for use with alternating currents, it is obvious that it is not necessarily limited to use in connection with a lamp of the character mentioned but 55 is susceptible of application in other relations as well. I therefore do not wish to be limited to the exact details shown and described since various modifications thereof both as to details of construction and mode 60 of application may be made without departing from the spirit of my invention.

What I claim as new and desire to secure by Letters Patent of the United States, is,

1. The combination of an exhausted envelop, main electrodes therefor, starting electrodes therefor, and means for impressing a high voltage upon a main electrode and one of the starting electrodes. 65

2. The combination of an exhausted envelop, a main mercury electrode, and two starting electrodes in proximity to said main electrode, one of said starting electrodes being of non-vaporizable material and the other of mercury. 70

3. The combination of a plurality of main electrodes one of which is adapted to generate a vaporous conducting medium, additional or starting electrodes, a transformer connected to one of said additional or starting electrodes, and means for supplying the primary of the transformer with current flowing to said main electrodes. 75 80

4. The combination of electrodes, a source of alternating current connected to said electrodes, inductance coils in circuit between said source and said electrodes, and a transformer having its primary in shunt to one of said inductance coils and its secondary connected to two of said electrodes. 85

5. The combination of an envelop, a body of mercury in said envelop, electromagnetically-actuated means for separating said mercury into separate bodies, and a solid electrode located in proximity to the region of such separation. 90 95

6. The combination of alternating-current mains, an envelop provided at one end with electrodes connected respectively to said mains, a starting electrode located in proximity to the first-mentioned electrodes, inductance coils connected in series across said mains, a common cathode connected to a junction between said coils, means for impressing a high voltage between said starting electrode and said common cathode, and means for producing an initial generation of ionized vapor in order to enhance the effect of said starting voltage. 100 105

7. In an alternating-current lamp, the combination of a mercury electrode, and a plurality of non-vaporizable electrodes arranged adjacent to each other, one of said electrodes having a conductor of small cross-section depending therefrom. 110

8. In a vapor electric apparatus, the combination of electrodes, a source of alternating-current connected to said electrodes to supply current thereto, and means traversed by a part only of said current for impressing a high voltage upon the apparatus. 115

9. The combination with an exhausted envelop, of a plurality of working positive electrodes, a common negative electrode, a plurality of starting electrodes, and current actuated means for setting said apparatus into operation. 120 125

10. The combination of a sealed envelop, a plurality of working positive electrodes therein, a common negative electrode, and a plurality of starting electrodes one at least 5 of which is adapted to make and break contact with the negative electrode, said starting electrodes being adapted, when supplied with current, to maintain an arc from said negative electrode for an indefinite period.
- 10 11. In an alternating current mercury

vapor apparatus, the combination of a negative electrode, a plurality of main electrodes, with two differently functioning supplementary electrodes.

In witness whereof, I have hereunto set 15 my hand this 20th day of June, 1918.

OSIAS O. KRUH.
